FIG. 4

FIG. 5

FIG. 6

FIGURE 1 is a perspective view of a chair showing my design wherein the backrest support members are arcuate and the leg members are inset with respect to the side edges of the seat;

FIGURE 2 is a front elevational view;

FIGURE 3 is a side elevational view of the chair of FIGURE 1;

FIGURE 4 is a rear elevational view;

FIGURE 5 is a top plan view;

FIGURE 6 is a bottom plan view;

FIGURE 7 is a front elevational view of the chair wherein the vertical portions of the backrest supports are straight and the top surfaces of the leg members are substantially outset with respect to the marginal side edges of the seat member; and

FIGURE 8 is a side elevational view of the chair of FIGURE 7.

The dominant features of my design reside in those portions shown in full lines on the drawing.

I claim:

The ornamental design for a chair, substantially as shown and described.
